UNITED STATES PATENT OFFICE.

GEORGE FULTON, OF WINNIPEG, MANITOBA, CANADA.

WOODEN FLOOR-COVERING.

1,028,703.

Specification of Letters Patent.

Patented June 4, 1912.

Application filed April 6, 1911. Serial No. 619,360.

To all whom it may concern:

Be it known that I, GEORGE FULTON, of the city of Winnipeg, in the Province of Manitoba, Canada, have invented certain new and useful Improvements in Wooden Floor-Coverings, of which the following is a specification.

The object of my invention is to produce a cheap and durable wood carpet which may be turned out in a variety of artistic patterns and which when laid will be less liable to warp, crack or curl than ordinary marquetry.

I attain my object by means of the process hereinafter described and illustrated in the accompanying drawings which results in the production of a wooden floor covering having the desired characteristics.

Figure 1 is a perspective view of a compound prismatic wooden block, illustrating the first step in the process of forming a floor covering. Fig. 2 is a perspective view of a compound slab formed by longitudinally slicing the compound block shown in Fig. 1. Fig. 3 is a compound prismatic block formed by cementing together a number of the slabs shown in Fig. 2. Fig. 4 is a perspective view of a single section of the covering formed by slicing the compound block shown in Fig. 3, as indicated in the dotted lines in that figure. Fig. 5 is a perspective view showing four sections of the flooring as they are laid together on the floor.

In the drawings like letters of reference indicate corresponding parts in the different figures.

The first step in the production of my flooring is to take a number of slabs of wood A and cement them together to form a compound prismatic block such as shown in Fig. 1. As it is my purpose to produce a patented floor covering certain of the slabs are made of strongly colored wood or else of wood to which the desired color has been given by steam dyeing or otherwise. In order to properly produce the pattern desired it is necessary that a number of prismatic blocks be formed in which the colored slabs are differently arranged to produce the necessary variation of pattern. These compound blocks are sliced endwise, as shown in dotted lines in Fig. 1, to produce the compound slabs B shown in Fig. 2. A number of the compound slabs B are then cemented together to produce the compound block

shown in Fig. 3, which block is thus made up of a number of slender prisms of wood all securely cemented together and displaying a pattern whose special figures depends on the special arrangement of the woods in the previous steps of the process. The next and most distinctive step in my process is the slicing of the compound prismatic block, shown in Fig. 3, transversely of the block and at an acute angle to the end of the block. In dotted lines in Fig. 3 I have illustrated this method of slicing the block. As the result of this slicing I obtain the compound floor sections C, such as shown in Figs. 4 and 5, in which the sides form right angles with the top and bottom, but in which the ends, though parallel, are not at right angles with the top and bottom.

While I prefer that the wood shall be all arranged so that the end grain appears at the top and bottom of the floor section C, yet for the purpose of securing variety in the patterns some cross grained wood might be employed in forming the original prismatic blocks, such as shown in Fig. 1.

The flooring is laid in the following manner. A row of floor sections C are laid with the ends suitably matching. Next to it is laid a similar row of sections in a reverse position to the ends of the sections of the adjoining row, and this reversal of the position of the floor sections in alternate rows is carried out all across the floor. The result is to form a lock all across the floor, where the sections adjoin transversely of the direction in which the sections are laid, as shown at the left hand in Fig. 5 where a projecting dove-tailed tongue a is shown next to an undercut or dovetailed recess b, the next adjoining sections presenting the same features in reverse position to engage the tongue and recess respectively. I find that this construction of the flooring makes the floor much less liable to check, warp or curl up. The possibility of securing this advantage is obtained through the diagonal slicing process I have hereinbefore described. Another advantage of this diagonal slicing is that for a given thickness of floor covering I secure in at least one direction in each block a much larger area of surface in the cemented joints between the pieces of which the block is made up. This renders each floor section C much less liable to split up than would otherwise be the case, for the better securing together of the parts

in the one direction tends also to strengthen the block against disintegration in the other direction.

The finished flooring, owing to the surface presenting the end grain of the wood, is much more durable and softer to the tread than ordinary hardwood or marquetry floors and is capable of taking a very satisfactory finish. As the floors may be produced in a variety of patterns either with or without a border, very artistic results may be produced, and as the small wooden slabs or blocks from which the original compound block shown in Fig. 1 is produced may be obtained much more cheaply than larger sized wood the cost of the flooring is comparable with any other first-class wooden floor covering.

I find it will be most convenient to make each section C represent only part of a pattern so that a plurality of sections, say four, will be required to make up a unit of the pattern. I propose therefore, to secure each group of sections C to a backing D (see Fig. 5) preferably of cotton or other suitable fabric as an equivalent for the textile fabric leather, rubber paper or any other continuous more or less pliable substance may be employed. This backing not only unites the parts of each pattern unit but aids materially in laying the flooring as a surface is provided which takes glue well without

the moisture penetrating to and swelling the wood.

I have referred to the fact that the slabs 35 of wood may be colored by steam dyeing or other suitable process. This enables me to bring up the color of inferior specimens of any wood to look equal to the best and also enables me, by dyeing cheap woods of the 40 color of the more expensive woods to produce a party-colored floor covering of cheap material which will look as well as if made from the choicest hardwoods.

It will be understood, of course, that the 45 finished product is applicable to other purposes than floor covering such as stair-treads, table tops, wainscots and the like.

What I claim as my invention is:—

A floor covering section consisting of an 50 even number of compound slices of wood cut across the grain and formed with parallel beveled ends, the said slices being arranged in a plurality of rows with their beveled ends inclined in opposite directions in alternate rows, in combination with a continuous backing to which the said slices are cemented.

Dated at Toronto this 3rd day of April 1911.

GEO. FULTON.
